UNITED STATES PATENT OFFICE

JOSEPH J. COSIN, OF NEWARK, NEW JERSEY

DESIGN FOR A COMBINED SET OF POWDER PUFFS AND CONTAINER THEREFOR

Application filed April 13, 1929. Serial No. 30,888. Term of patent 7 years.

To all whom it may concern:

Be it known that I, JOSEPH J. COSIN, a citizen of the United States and a resident of Newark, Essex County, State of New Jersey, have invented a new, original, and ornamental Design for a Combined Set of Powder Puffs and Container Therefor, of which the following is a specification, reference being had to the accompanying drawing, forming part thereof.

The figure is a face view of a combined set of powder puffs and container therefor showing my new design.

I claim:

The ornamental design for a combined set of powder puffs and container therefor, substantially as shown.

JOSEPH J. COSIN.
